UNITED STATES PATENT OFFICE.

JAMES J. VERKA, OF CHICAGO, ILLINOIS.

ROCKING-CHAIR.

Application filed April 6, 1925. Serial No. 21,083.

This invention relates to new and useful improvements in attachments for furniture and more particularly to rocking chairs and the like. The main object of my invention 5 is the provision of an attachment for rocking chairs having a compressible back portion wherein the action of the person occupying the rocking chair against the compressible back portion will be utilized for compressing air to be used for cooling purposes. Another object of my invention is the provision of an attachment for rocking chairs having a compressible back portion wherein the movement of the person's body during 15 the rocking operation will actuate the compressible back portion and this action will be utilized for compressing air, adapted to be used in warm weather as a cooling medium.

20 A further object of my invention is the provision of a device set forth above wherein there is included a storage chamber in which the compressed air is stored wherein manually operated means is employed for 25 utilizing the air stored within the chamber as a cooling medium.

With the above and other objects in view, my invention consists in the novel features 30 of construction and the combination of parts to be hereinafter more fully described, pointed out in the claims and shown in the accompanying drawings, in which:—

Fig. 1 is a sectional view taken through the rocking chair showing my improved attachment incorporated in the construction 35 of the chair.

Fig. 2 is a front elevation of the chair, as parts thereof are broken away.

Fig. 3 is a detailed section on the lines 40 3—3 of Fig. 2.

Fig. 4 is an enlarged sectional view taken through the portion of the back of the chair showing the manner of releasing the air from the storage chamber.

45 Fig. 5 is a front elevation, parts being broken away and illustrated in section for illustrating the modified form of my invention.

Fig. 6 is a side elevation illustrating another form of my invention, parts thereof being broken away and illustrated in cross-section.

Fig. 7 is a detailed section on the lines 7—7 of Fig. 6.

Referring more particularly to the drawings, it will be noted that my improved attachment is preferably incorporated in that type of rocking chair having a compressible back portion, the chair in the present instance including the usual rockers 1, with the front legs 2 and the rear legs 3, extending upwardly therefrom to support the seat 4 and side arms 5. The back is formed of a flexible covering 6 supported upon the outer ends of the coiled springs 7 and inner ends 65 of which are connected to the back portion 8. From this it will be noted that when the person is rocking in the chair, the forward movement of the rocker will have a tendency to cause the back of the person to move forwardly allowing the springs 7 to expand upon the flexible covering and will compress the springs 7 upon the backward movement, an action which is bound to take place in rocking chairs having a compressible or 70 flexible back.

In the back portion 8 of the chair a one-way valve 9 is mounted which opens into the chamber 10 between the flexible means 6 and the back of the chair and within this 80 chamber is the transverse partition 11 forming the chamber 12 at the top and disposed between the chambers 10 and 12 within the partition 10 is the one-way valve 13 permitting the air to pass into the chamber 12 85 but preventing any backward movement of the air into the chamber 10, and both valves 9 and 13 being spring controlled as illustrated so that it will normally retain them in a seated position. From this construction it will be apparent that upon the expansion of the springs 7 the valve 9 will be opened, thus permitting the air to enter the chamber 10 so that when the springs 7 are moved to a contracted position the valve 9 90 will be closed and the pressure of the air in the chamber 10 will be forced against the valve 13 and opening the same, allowing the air to pass into the chamber 12 until the springs 7 reach the limit of contraction according to the weight placed thereon, at 95 which time the valve 13 will be moved to a seated position.

An outlet 14 is provided for chamber 12

which communicates with the conveying tube 15 which may be of any size and length for conveying the air from the chamber 12 to the place desired.

5 A spring retained valve 15' normally closes the outlet 14 and is actuated by means of a reciprocating rod 16, which is slidably mounted within the back portion and has at its lower end an outwardly projecting arm 17 adapted to be engaged by one end of the pivoted bar 18 for raising and lowering the rod 16 to open the valve 15' and permit the closing of the valve through the tension of the spring 19. The bar 18 extends parallel with one of the side arms 5 and the forward end thereof, is provided with the finger piece 20 adapted to be actuated by the party using the chair when it is desired to open and close the valve 15'. The opening and closing movement of the valve 15 is adjustable by means of a disc 21 mounted upon the rod 16 and retained in various positions by means of the lock nuts 22, said disc when in a normal position for closing the valve 15 rests 25 upon the washer 23 carried by the back portion of the chair.

From the above it will be apparent that I have provided a simple and inexpensive device which may be readily incorporated 30 in the construction of rocking chairs having a flexible or compressible back portion normally retained in an operative position by means of coiled springs wherein the movement of a person's body against the flexible 35 covering 6 during the rocking operation, will compress sufficient air for use as a cooling medium and wherein the use of the air is manually controlled by the party occupying the chair.

40 In Fig. 5 I have illustrated a slightly modified form of the invention wherein a one-way valve 9' is incorporated in the back of the chair and a one-way valve 13' is disposed between the chamber 10' and the 45 chamber 12'. Communicating with the chamber 12' is the flexible means 24 whereby the air compressed in the chamber 12' will be readily conveyed thru the tube 23 and when the device is not in use, an ordinary 50 clamping member 25 is attached to the tube adjacent the outer end thereof, for cutting off the escape of the air.

In Fig. 6, I have illustrated another form 55 of the invention wherein the air is compressed from chamber 10' and passes directly upwardly to the tube 26 which is connected to a guide nozzle 27 at its inner end so that as the air is compressed in chamber 10' it will be directly utilized. In this form 60 of the invention it will be noted that a movable drawer 28 is mounted beneath the arm 5' and may be utilized for various purposes.

While I have shown and described the preferred form of my invention, it will be obvi-

ous that various changes in the details of 65 construction and in the proportions may be resorted to for successfully carrying my invention into practice without sacrificing any of the novel features or departing from the scope of the appended claims.

Having thus described my invention, what I claim is:—

1. In combination a chair, a back therefor, and a flexible back-rest carried by the back and yieldably retained in spaced relation with the back to form a chamber, means carried by the back for controlling the entrance of air into said chamber thru movement of the flexible member and means for controlling the outlet of air from said chamber.

2. In combination a chair, including an upright back portion, a flexible member normally disposed in spaced relation with the back, yieldable members normally maintaining the flexible portion in spaced relation with the back, whereby pressure against the flexible portion of the back will contract the yieldable members and means for controlling the inlet and outlet of air relative to said chamber upon movement of the flexible portion toward and away from the back.

3. In combination a rocking chair, an up-standing back having an opening therethru, a yieldably mounted flexible portion normally retained in spaced relation with the back forming a chamber, a one-way valve in the opening controlling the inlet of air into the chamber, a second chamber above the first chamber, a one-way valve controlling the passage of air from the first chamber into the second chamber, the said valves being operated thru the contraction and expansion of the flexible portion, relative to the back member.

4. In combination a rocking chair, an up-standing back having an opening therethru, a yieldably mounted flexible portion normally retained in spaced relation with the back forming a chamber, a one-way valve in the opening controlling the inlet of air into the chamber, a second chamber above the first chamber, a one-way valve controlling the passage of air from the first chamber into the second chamber, the said valve being operated thru the contraction and expansion of the flexible portion, relative to the back member, and manually controlled means for regulating the discharge of air from the second chamber.

5. In combination a rocking chair, an up-standing back yieldably mounted flexible portion carried by the back and normally maintained in spaced relation therewith to provide a chamber, said chamber having an inlet and a valve controlling the entrance of air into the chamber upon movement of the flexible portion away from the back and

whereby the movement of the flexible portion toward the back will discharge the air thru the outlet opening.

6. A rocking chair including an upstanding back having an opening therethru, and yieldably mounted flexible portion carried by the back and normally maintained in spaced relation therewith, a partition member between the back and flexible portion forming separate chambers, a one-way valve controlling the entrance of air into the one

of said chambers, a one-way valve carried by the partition for controlling the passage of air from the one chamber to the other, a one-way valve in the second chamber, and manually operated means for controlling the movement of the last mentioned one-way valve for regulating the passage of air from the second chamber. ¹⁵

In testimony whereof I affix my signature.

JAMES J. VERKA.
